UNITED STATES PATENT OFFICE.

WILLIAM H. BIRGE, OF FRANKLIN, PENNSYLVANIA.

APPARATUS FOR MANUFACTURING OXIDES OF METALS.

SPECIFICATION forming part of Letters Patent No. 468,216, dated February 2, 1892.

Application filed February 18, 1891. Serial No. 381,936. (No model.)

To all whom it may concern:

Be it known that I, WILLIAM H. BIRGE, of Franklin, in the county of Venango and State of Pennsylvania, have invented a new and 5 Improved Apparatus for Manufacturing Oxides of Metals, of which the following is a full, clear, and exact description.

The object of the invention is to provide a new and improved apparatus for manufacturing oxides from readily-oxidizable metals, and which is simple and durable in construction, effective in operation, and forms the oxides at a very low cost.

The invention consists of a nozzle provided 15 with a disk extending into a spraying-recess and having a central aperture for the passage of the molten metal to the top of the said disk and an air-blast connection leading to the said recess under the said disk.

20 The invention also consists in certain parts and details and combinations of the same, as will be described hereinafter, and then pointed out in the claims.

Reference is to be had to the accompanying 25 drawings, forming a part of this specification, in which similar letters of reference indicate corresponding parts in all the figures.

Figure 1 is a sectional side elevation of the 30 improvement. Fig. 2 is an enlarged sectional side elevation of the nozzle on the line $x-x$ of Fig. 3. Fig. 3 is a plan view of the same, and Fig. 4 is an inverted sectional plan view of the same on the line $y-y$ of Fig. 2.

The improved apparatus is provided with 35 a vertically-arranged oxidizing-chamber A, preferably made in the shape of an inverted truncated cone and provided at its lower end with the cylindrical part B, resting on a ring-shaped bed-plate C, supported on a wall D, 40 forming a space E, connected with retorts or furnaces generating hot air, which can pass into the said space E. In the lower end of the cylindrical part B is held the nozzle F, provided with a plate G, resting on an inward projection of the bed-plate C and provided 45 on its under side with a circular offset H, on which screws a pipe I, connected with a hot-air-blast supply. The pipe I discharges into a series of openings J, formed in the offset H and the plate G and leading into a spraying-recess K, formed in the hub L of a plate N, 50 supported on top of the plate G, as is plainly

shown in the drawings. Into the spraying-recess K extends a disk O, somewhat smaller in diameter than the said recess, so as to form 55 between the walls of the said recess and the outer edge of the disk a space P, through which passes the hot-air blast passing through the pipe I and the openings J. The disk O is secured or formed with its stem on the top 60 of the plate G, and in the said disk and the said plate is formed a passage Q, connected with a pipe R, provided with a stop-cock R' and leading to the bottom of the vessel S, containing a suitable molten metal, preferably 65 lead.

The vessel S is arranged somewhat above the disk O, so that by opening the stop-cock R' the metal readily flows through the pipe R and the passage Q onto the top of the disk 70 O and there spreads out to the edge of the disk to be taken up by the hot-air blast passing upward through the space P.

In the plates G and N are formed registering openings T, connecting the space E with 75 the cylindrical part B, so that hot air can pass up into the oxidizing-chamber A.

The operation is as follows: When the hot-air blast passes under pressure through the pipe I and the openings J into the spraying-recess K and the molten metal is permitted to flow to the top of the disk O at the same time, then the air-blast in passing through the space P engages the outer edge of the molten metal spread on the disk O, thereby carrying upward small particles of the molten metal, which is thus brought to a finely-communited condition, in which it is readily oxidized and carried off by the force of the blast to the condensing-chamber connected with the upper 80 end of the oxidizing-chamber. The hot blast passing into the cylindrical part B and the oxidizing-chamber A causes a circulation of air through the retorts or furnaces connected with the space E, so that the hot air is drawn 85 from the said space E and openings T into the oxidizing-chamber O at or near its lower end, thus assisting in maintaining the required heat to perfectly oxidize the finely-communited metal. In this manner an air-compressor is not required for forcing the necessary amount of air into the oxidizing-chamber A, and only such a force of hot-air 90 blast is required as is necessary to spray the 95 100

molten lead on top of the disk O and to force the sprayed metal up into the oxidizing-chamber.

Having thus described my invention, what I claim as new, and desire to secure by Letters Patent, is—

1. In an apparatus for manufacturing oxides of metals, a nozzle comprising a disk extending into a spraying-recess and having a central aperture for the passage of the molten lead to the top of the said disk, and a hot-air-blast connection leading to the said recess under the said disk, substantially as shown and described.
- 15 2. In an apparatus for manufacturing oxides of metals, a nozzle comprising a plate arranged on the lower end of the oxidizing-chamber and having a spraying-recess, a disk somewhat smaller in diameter than the diameter of the said recess and extending into the said recess and provided with an inlet-opening for the passage of the molten metal to the top of the said disk, and a hot-air-blast connection leading to the said recess under the said disk, substantially as shown and described.
- 25 3. In an apparatus for manufacturing oxides of metals, the combination, with an oxidizing-chamber connected at its lower end with a hot-air supply, of a nozzle held in the lower end of the said oxidizing-chamber and

formed with openings to permit the hot air to pass into the oxidizing-chamber, a disk extending into a spraying-recess in the said nozzle and having an inlet-opening for the passage of the molten metal to the said disk, and a hot-air-blast connection leading to the said spraying-recess under the said disk, substantially as shown and described.

4. In an apparatus for manufacturing oxides of metals, the combination, with an oxidizing-chamber connected at its lower end with a hot-air supply, of a nozzle held in the lower end of the said oxidizing-chamber and formed with openings to permit the hot air to pass into the oxidizing-chamber, a disk extending into a spraying-recess in the said nozzle and having an inlet-opening for the passage of the molten metal to the said disk, a hot-air-blast connection leading to the said spraying-recess under the said disk, a pipe provided with a valve and connecting with the said inlet-opening, and a receptacle containing the molten metal and connected at its bottom with the said pipe, the said vessel being arranged above the said disk, substantially as set forth.
